TONGUE BLADE

Edward J. Hill, 1660 Lochridge, Bloomfield Hills, Mich.

Filed Dec. 9, 1963, Ser. No. 77,725

Term of patent 14 years

(Cl. D83—12)

FIG. 1

FIG. 2

FIG. 3

FIG. 4

FIG. 1 is a top plan view of a tongue blade embodying my new design; the undisclosed bottom is substantially the same as the top;

FIG. 2 is a side elevational view thereof;

FIG. 3 is an end elevational view taken from left of FIG. 2; and

FIG. 4 is an end elevational view taken from the right of FIG. 2.

I claim:

The ornamental design of a tongue blade, substantially as shown and described.
